DESIGN FOR A REED FOR MUSICAL INSTRUMENTS

William S. Baber, Auburn, Ind.

Application November 26, 1941, Serial No. 104,342

Term of patent 14 years

To all whom it may concern:

Be it known that I, William S. Baber, a citizen of the United States, residing at Auburn, in the county of De Kalb and State of Indiana, have invented a new, original, and ornamental Design for Reeds for Musical Instruments, of which the following is a specification, reference being had to the accompanying drawing, forming part thereof.

Figure 1 is a top plan view of a reed for musical instruments, showing my design.

Figure 2 is a longitudinal cross-sectional view taken along line 2—2 of Figure 1 and in the direction of the arrows.

Figure 3 is a horizontal cross-sectional view taken along line 3—3 of Figure 1 and in the direction of the arrows.

I claim:

The ornamental design for a reed for musical instruments, as shown.

WILLIAM S. BABER.
